(57) **CLAIM**

The ornamental design for a raised access floor panel with embedded sensors, as shown and described.

DESCRIPTION

FIG. 1 is a top isometric view of a raised access floor panel with embedded sensors.

FIG. 2 is a bottom isometric view of the raised access floor panel with embedded sensors.

FIG. 3 is a top view of the raised access floor panel with embedded sensors.

FIG. 4 is a bottom view of the raised access floor panel with embedded sensors.

FIG. 5 is a right side view of the raised access floor panel with embedded sensors.

FIG. 6 is a left side view of the raised access floor panel with embedded sensors.

FIG. 7 is a front view of the raised access floor panel with embedded sensors; and,

FIG. 8 is a rear view of the raised access floor panel with embedded sensors.

Any broken line portions of the disclosure are for illustrative purposes only and form no part of the claimed design.
